ROTARY MACHINE

George E. Campbell, Chattanooga, Tenn., assignor
to The Wheland Company, Chattanooga, Tenn.,
a corporation of Tennessee

Application May 6, 1936, Serial No. 78,276

5 Claims. (Cl. 255—23)

This invention relates to an improvement in rotary machines of the type employed in the drilling of oil wells, and more particularly to a rotary machine which is fully enclosed and is so constructed as to withstand the severe shocks imposed upon present day well drilling apparatus.

An object of the present invention is to provide a continuous bath of oil or other lubricant for all bearings and moving parts, insuring a quiet running machine with a minimum of friction. With the elimination of friction, very little wear will occur, and the rotary will operate continuously for a long period of time with a minimum of care.

Another object of the invention is to provide 15 separate oiling compartments, each of which is entirely separate from the others, so that different lubricating compounds may be used for the pinion shaft bearings, the gears, and the thrust roller bearing, and to improve the construction of 20 the rotary machine to provide these separate chambers.

One of the oil openings through which lubricant is supplied to the gears, is so arranged as to form a peephole, to permit ready inspection of the meshing of the gears, because the life of the gears and the noise that they make are very largely determined by the meshing of the pinion with the ring gear. Provision is also made for the lubrication of the skirt of the table in connection with the 30 lubrication of the thrust roller bearings.

Still another object of this invention is to improve the construction of the rotary machine, to simplify its construction, and to enable it to operate successfully with a minimum of care and to 35 withstand the severe shocks imposed upon the rotary in well drilling operation.

Among the improved features of this rotary machine is a pinion shaft assembly which provides for adjustment of the pinion relative to the ring gear in order to obtain proper meshing thereof for proper running of the machine and especially for the elimination of noise. Provision is made in this assembly for the mounting of the pinion shaft so as to maintain proper alignment 45 of the parts.

Another improved feature of this rotary is the ring gear locking device which makes provision for direct locking of the ring gear to the base, which simplifies the pinion shaft assembly and 50 removes from the pinion bearings all shocks incident to locking. A locking pin is slidably mounted in the base in position to be raised into meshing engagement with the teeth of the ring gear for locking the ring gear and table against rotation. 55 Other improved features of the invention will be

set forth more particularly in the following description and claims. A preferred embodiment of the invention is illustrated in the accompanying drawings, in which:

Fig. 1 is a vertical longitudinal sectional view 5 partly in elevation, through the rotary machine, taken substantially on the line 1—1 in Fig. 2;

Fig. 2 is a top plan view of the machine with a portion of the table construction broken away to show the bearings and base structure; 10

Fig. 3 is an end elevation of the rotary machine;

Fig. 4 is a vertical sectional view of the ring gear locking device substantially on the line 4—4 of Fig. 2;

Fig. 5 is an end elevation of said locking device, 15 partly in section;

Fig. 6 is a top plan view of the pinion shaft assembly bearing box detached;

Fig. 7 is a face view thereof;

Fig. 8 is a vertical sectional view therethrough, 20 and

Fig. 9 is an enlarged sectional view of the hold-down ring structure partly broken away.

As indicated in the accompanying drawings, the base of the rotary machine is designated generally by the numeral 1, and is of one piece construction to mount and support the parts of the rotary machine. The base 1 is supported upon the usual longitudinally extending skids 2, which extend throughout the entire length of the machine, said skids being formed integral with the base, and being L-shaped in cross section, as shown in dotted lines in Fig. 3.

The base 1 has an upstanding flange 3 of annular shape and carrying an annular bearing raceway 4. The raceway 4 is formed by means of an annular bottom wall 5 from which inner and outer bearing retaining flanges 6 and 7 extend upwardly, being spaced apart horizontally to define the bearing raceway 4. Seated in the raceway 4 35 is a bearing ring 8 having tapered roller bearings 9, mounted and operating therein. A cooperating roller bearing race ring 10 rides upon the roller bearings 9, and has a depending flange 11 vertically telescoping the upper edge of the 40 outer flange 7.

The race ring 10 supports the rotary table 12 which is mounted thereon, having a groove 13 therein receiving the race ring 10, and a depending flange 14 is formed on the rotary table and 50 extends in vertical alignment with the flange 7 but spaced slightly therefrom for free operation.

The base 1 is provided with an annular wall 15 which extends outwardly and upwardly from the periphery of the flange 3, forming a gear lubri- 55

cant chamber 16. The annular chamber 16 has one side thereof in communication with a sump 17 depressed in the base 1, so as to drain the lubricant from the annular gear chamber back into the sump.

5 The upper edge of the wall 15 overlaps a depending flange 18 formed on the periphery of the table 12, preventing the introduction of foreign matter, such as mud, water, and the like, into the 10 rotary machine or the gear lubricant chamber 16. Spaced radially from the table 12 is a guard ring 19 carried by a plurality of upstanding lugs 20 secured by bolts or screws 21 to the periphery of the wall 15. This guard ring 19 protects the 15 table from injury and protects the operator from the rotation of the table.

The table 12 carries the usual ring gear 22 which operates in the gear chamber 16 and meshes with a pinion 23 mounted on the inner 20 end of the pinion shaft 24. The pinion 23 dips into the oil sump 17, so as to receive a bath of oil or lubricant and to transfer said lubricant to the ring gear 22, from which any lubricant dripping off will be drained back into the sump through 25 the annular chamber 16. The outer end of the pinion shaft 24 carries the usual sprocket wheel 25 to receive power for the operation of the machine.

The pinion shaft 24 is mounted in a pair of 30 axially spaced bearings designated generally by the numerals 26 and 27, which bearings are mounted in a bearing sleeve 28. The bearing assembly 26 is locked relative to the pinion shaft 24 by means of a lock nut 29, which is threaded 35 on the pinion shaft and abuts the inner race 26 of the bearing assembly. The bearing sleeve 28 is adapted to enclose a lubricant chamber for the pinion shaft assembly, for which purpose grease seals 30 and 31, close the opposite ends 40 of the bearing sleeves. Lubricant is supplied to this chamber within the bearing sleeve through the opening which receives the screw plug 32, and upon removal of the latter.

One end of the bearing sleeve 28 is provided 45 with a pair of laterally extending feet 33 which feet 33 are mounted on guides 34 in the base 1 to which they are secured by screws or bolts 35 which extend through slots 36 in the feet and into the base for holding the bearing sleeve 28 securely in place. The slots 36 are provided in order to permit longitudinal adjustment of the bearing sleeve relative to the base upon loosening the bolts or screws 35, as will be described hereinafter. Shims 37 may be provided, as desired 55 for raising or lowering the complete pinion shaft assembly relative to the base.

The inner end of the bearing sleeve 28 is slidably received in a bearing box 38 for longitudinal adjustment relative thereto. The bearing sleeve 60 is threaded as at 39 and is fitted with a split nut 40 on the threaded portion 39. A flange 41 on the split nut 40 engages in a groove 42 in the bearing box 38, and is movable axially therein.

The annular wall 15 has a radial opening 43 in 65 a side thereof receiving the pinion shaft assembly, and the bearing box 38 abuts against the face of the wall 15 surrounding the opening 43. The bearing box is secured to the wall 15 by screws or bolts 44 which extend through slots 70 45 in a flange 46, on the bearing box 38 to permit vertical adjustment of the bearing box and obtain proper alignment of the parts. The bearing box 38 is also provided with laterally extending feet 41, mounted in guide ways 48 in the base, being 75 adjusted vertically by the shims 37. Bolts or nuts

49 secure the feet 41 to the base. As shown in Figs. 6 and 7, lugs 50 are formed on the inner end of the bearing box 38, and project into the opening 43 approximately in contact with the periphery thereof for insuring proper alignment of the bearing box.

The bearing box 38 is provided with a cap 51 complementary therewith and forming the top portion of the bearing box as shown in Fig. 8. The bearing box cap 51 is provided with an opening 52 therein extending laterally therethrough 10 and registering with the top portion of the opening 43, serving the two fold purpose of introducing lubricant such as heavy gear compound to the ring gear chamber 16 and sump 17 to provide lubrication for the gears, and also for permitting inspection of the gears, particularly the meshing of the pinion 23 with the ring gear 22, whereby proper adjustments can be made to obtain proper meshing of these gears. The life of the gears and 20 the noise that they make in operation is largely determined by their proper meshing. A cover 53 closes this opening 52 when not in use.

The pinion shaft assembly is adjusted bodily by the nut 40. Rotation of this nut 40 pushes 25 the bearing sleeve 28 with its assembly, including the pinion 23 and pinion shaft 24, axially to vary the meshing of the pinion relative to the ring gear or to move the pinion into or out of mesh therewith. This nut 40 may be adjusted during 30 rotation of the ring gear and pinion, so that the meshing of these gears can be quickly and properly adjusted for proper running and especially for the elimination of noise.

The table 12 carries the usual master bushing 35 designated generally by the numeral 54, the construction of which need not be described in detail.

Provision is made for locking the ring gear and table against rotation, for which purpose a 40 plunger 55 is slidably mounted in a vertical guide 56 in the base 1 and is provided with a tooth 57, on its upper end to engage between the teeth of the ring gear 22. This construction is shown more clearly in Figs. 4 and 5. The plunger 55 is provided with a transverse slot 58 therein intermediate its ends and at one end of the slot 58, the plunger is notched out as at 59 to receive a cam 60 which operates in this notch 59. The cam 60 is fixed on a cam shaft 61 extending 45 transversely through the slot 58 in the plunger and having one end thereof journaled in the base 1, beside the guide 56, while the other end of the cam shaft 61 is journaled in a bearing 62 secured to the base 1. The free end of the 50 cam shaft 61 carries a lever 63 for turning the shaft 61 and cam 60 in order to reciprocate the plunger 55 vertically into and out of engagement with the teeth of the ring gear 22. The lever 63 swings between the positions shown in Figs. 60 2 and 5, Fig. 2 representing the position of the lever when the plunger is lowered out of engagement with the ring gear, and Figs. 4 and 5 representing the position of the lever when the plunger is in engagement with the ring gear. 65 This forms an effective lock for the ring gear and table which makes it unnecessary to have a locking device associated with the pinion shaft assembly and thereby simplifies the latter while at the same time removing all shocks incident 70 to locking from the pinion bearings.

The table 12 is provided with a depending skirt 64 which is journaled in the bearing flange 6, as shown in Fig. 1, and the skirt 64 is also journaled in a bushing 65 pressed into a counterbore 75

65 in the base 1, so as to form a journal for the skirt portion of the table. The lower edge of the bushing 65 is provided with a flanged portion 66, against the lower face of which the hold-down filler ring 67 abuts, and being keyed to the skirt 64 as at 68, so as to rotate therewith. The undersurface of the flange 66 has annular grooves 69 which tend to form an oil seal between the hold-down filler ring 67 and the flange 66. The ring 67 has an upstanding flange 70 surrounding the periphery of the flange 66 and provided with annular grooves 71 in the inner surface of said flange 70, as a further means of confining the oil. The flange 66 is also provided with a deep annular groove 72 therein receiving an upstanding rib 73, formed on the upper surface of the ring 67 which cooperates with the grooves 69 and 71 for confining the oil in the bearing surface. The arrangement shown provides an up-thrust bearing between the ring 67 and the flange 66.

In order to hold the filler ring 67 in place, a hold-down ring 74 is screwed onto a threaded portion 75 at the lower end of the skirt 64. The hold-down ring 74 is screwed up to the desired extent in order to maintain a proper working clearance between the ring 67 and the flange 66, and then it is locked against further adjustment by means of a spring-pressed pin 76 carried by the hold-down ring 74 in position to enter one of a plurality of openings 77 spaced at intervals around the undersurface of the filler ring 67.

Interposed between the hold-down ring 74 and filler ring 67 is a spring retaining ring 78, which is relatively thin and is secured to the underside of the filler ring 67 but is slightly movable relative thereto. The retaining ring 78 has a plurality of coiled springs 79 carried on the upper surface thereof and extending into openings 80 in the undersurface of the filler ring 67. The purpose of these springs 79 is to press upward on the filler ring 67, keeping it in its uppermost position against the flange 66 of the bushing 65. The spring retaining ring 78 facilitates assembly 45 of the springs and holds them in place preparatory to putting on the hold-down ring 74. The tension of the springs is adjusted by screwing up the hold-down ring 74, which is thereafter locked in place by the locking pin 76. This forms an up-thrust bearing between the parts 66 and 67 and also provides a means for properly adjusting the vertical working clearance between the table and base. The hold-down filler ring 67 may be lubricated with heavy grease through an "Alemite" fitting 81, shown in Fig. 2.

The roller bearings 9 operate in a chamber 82 which is supplied with lubricant through a fitting 83 which may also be an "Alemite" fitting, and it is preferable that a medium grade of 50 "Alemite" lubricant be supplied to the chamber 82 and that the lubricant be maintained in the chamber at a height above the flange 6, so that it will find its way down along the periphery of the skirt 64 inside of the base and bushing 65, but it is stopped by the grease and seal between the parts 66 and 67.

The rotary machine is operated in the customary manner, power being applied through the usual sprocket chain to the sprocket wheel 70 25 for rotating the pinion shaft 24, pinion 23, and ring gear 22, and thereby turning the table

12 on the roller bearings 9. During such operation, the lever 63 will be in the position shown in Fig. 2 with the plunger 55 lowered out of engagement with the ring gear 22, but when it is desired to lock the table in a stationary position, the plunger 55 is raised as above desired. 5

I claim:

1. In a rotary machine, the combination of a bearing-box, a bearing sleeve movably connected thereto, a shaft rotatably supported in the bearing sleeve, a pinion thereon, and means surrounding the sleeve for moving the sleeve and the shaft endwise in the bearing-box, said means being swiveled to one and threaded to the other of said movably connected elements. 10

2. In a rotary machine, the combination of a bearing-box, a cylindrical bearing sleeve slidably mounted therein, a shaft rotatably mounted in the sleeve against endwise movement therein, the central portion at least of said sleeve being 20 exteriorly and circumferentially screw-threaded, and a nut having internal screw-threads constructed and adapted to turn on the threads of the sleeve, said nut having a swivel connection with the bearing-box. 25

3. In a rotary machine, the combination of a bearing-box, a cylindrical bearing sleeve slidably mounted therein, a shaft rotatably mounted in the sleeve against endwise movement therein, the central portion at least of said sleeve being 30 exteriorly and circumferentially screw-threaded, a nut having internal screw-threads constructed and adapted to turn on the threads of the sleeve, said nut having a swivel connection with the bearing-box, a pinion on one end of the shaft 35 and a gear on the opposite end of the shaft. 35

4. In a rotary machine, the combination of a base, an annular wall, a table rotatably mounted on the base and having a ring gear positioned within said annular wall, one side of the wall 40 having an opening, a two-part bearing-box constructed and adapted to cover said opening, means for adjusting the bearing-box relative to the opening in the annular wall, the bearing-box provided with laterally extending feet mounted 45 in guideways therefor in the base, an exteriorly threaded bearing-sleeve movably connected with the bearing-box, and a split adjusting device rotatably connected to the bearing-box and rotatable on the threads of the bearing-sleeve for 50 moving the latter endwise with respect to the bearing-box.

5. The combination of a cylindrical wall having an opening in one side, a ring gear, a bearing-box made in two parts adjustably secured 55 over the opening, the upper part of the bearing box having an opening which registers with the top portion of the opening in the cylindrical wall for inspection and to receive lubricant, an externally threaded bearing-sleeve extending 60 through the bearing-box, a split nut mounted to turn on the threads of the sleeve and having an annular flange which turns in a groove in the box, the split nut located in close proximity to the opening in the box so that an operator can 65 watch the adjustment of gears adjacent the opening while turning the split nut, and a shaft journaled in the sleeve having a bevel pinion thereon which meshes with a ring gear within the wall. 70

GEORGE E. CAMPBELL.
